F. M. VOLK.

CAR SEAL.

APPLICATION FILED JULY 19, 1920.

1,354,634.

Patented Oct. 5, 1920.

UNITED STATES PATENT OFFICE.

FRANCIS M. VOLK, OF SAN FRANCISCO, CALIFORNIA.

CAR-SEAL.

1,354,634.

Specification of Letters Patent.

Patented Oct. 5, 1920.

Application filed July 19, 1920. Serial No. 397,420.

To all whom it may concern:

Be it known that I, FRANCIS M. VOLK, a citizen of the United States, residing at San Francisco, in the county of San Francisco and State of California, have invented new and useful Improvements in Car-Seals, of which the following is a specification.

My invention relates to a car seal principally adapted for officially sealing railway car doors, although useful for other purposes, embodying a flexible metal band having one end rigidly secured to a lock and its other end provided with a catch adapted to be operatively projected into one end of the lock for automatically locking itself therein.

One of the objects of my invention is to provide a seal, of a class that is well known, that is positive in action, one that requires no tools of any kind to attach or lock it, and one that is inexpensive to manufacture.

A further object of the invention is the provision of a seal that is positively unlockable, and that can be opened only by breaking it.

With the foregoing and other objects and purposes in view which will appear as the description proceeds, my invention resides in the combination and arrangement of parts and in the details of construction hereinafter described and claimed, it being understood that changes in the precise embodiment of the invention can be made within the scope of what is claimed without departing from the spirit of the invention.

In the accompanying drawings:—

Figure 1 is a view in elevation of the seal, locked.

Fig. 2 is a median sectional view of the lock member of the seal, showing the free end of the band partly entered in the lock, portions of the band being broken away.

Fig. 3 is a sectional view similar to view shown in Fig. 1, but with the locking end of the band fully entered into the lock.

Fig. 4 is a sectional view on line $g-g$, Fig. 3.

Fig. 5 is a cross section on line $a-a$, Fig. 2.

Fig. 6 is a cross section on line $d-d$, Fig. 3.

Fig. 7 is a view on line $e-e$, Fig. 2.

Fig. 8 is a plan view of one end of the band.

Fig. 9 is a cross section on line $h-h$, Fig. 1.

Fig. 10 is a perspective view of the locking spring.

Fig. 11 is a perspective view of the spring supporting member.

Figs. 2 to 11, both inclusive, being drawn 60 on a scale substantially larger than Fig. 1.

Referring now to the drawings in detail, throughout which like reference characters indicate like parts—

The numeral 1 designates a lock embodying a housing comprising a lower wall 2, side walls 3, top wall sections 4, 5 and 6, an offset 7, and openings 8 and 9.

Into the opening 8 is projected one end of metal ribbon or band 10, which is rigidly secured between the upper side of one end of the wall 2 and the wall section 6, by electrowelding or by other suitable means such as soldering or the like.

While I prefer to construct the ribbon 10 75 of pliable sheet metal, preferably non-resilient, other material may be employed if desired.

The free end of the ribbon 10 is provided upon its edges with oppositely disposed 80 notches 11, into which are snugly fitted a pair of oppositely disposed projections 12 on one end of a spring-supporting member 13. Said projections 12 adapted to be folded downwardly upon the upper side of the 85 ribbon 10. In Fig. 11, the projections 12 are shown in a vertical position, before their final bending downwardly upon the ribbon.

The free end of the member 13 is rolled 90 back so as to form an overhanging lip 14, between which lip and the member 13 is frictionally clamped one end of a locking spring 15, the free end of which spring curves upwardly at a substantial incline 95 with the main body portion of the member 13 (see Fig. 3).

To operate my invention, to facilitate describing which I will state that by "normal position" is meant the position of the seal 100 when it is open or unlocked, that is to say when the locking member of the ribbon 10 including the member 13 and spring 15 are free from engagement with the lock 1, the ribbon 10 is operatively engaged with suitable fittings on the door or means desired to be authoritatively sealed, and the said member 13 and spring 15 projected into the opening 9 causing the spring 15 to compress against the tension of itself (see Fig. 2) 110

until its free end passes inwardly beyond the offset 7, thereby permitting the spring to extend again into its normal position and thereby permanently locking itself against 5 said offset (see Fig. 3).

I am aware that car door seals employing flexible bands or ribbons having means for interlocking their ends, have been used before, I therefore do not claim this broadly, 10 but what I do claim and desire to secure by Letters Patent is:—

1. A car seal of the character described, comprising a flexible ribbon having one end permanently secured to a lock, said lock 15 provided with an interior chamber, a spring-supporting member permanently secured to the other end of the ribbon, and a locking spring permanently secured to the free end of the spring-supporting member.

20 2. A car seal of the character described, comprising a flexible ribbon, a lock, the lock having an opening extending through from one end to the other, an intermediate section of said opening being vertically extended 25 thereby forming an offset, a fixed connection between one end of the ribbon and one end of said opening, a spring-supporting member fixedly secured to the other end of the ribbon, and a spring having one end fixedly 30 secured to the free end of said member, the free end of the spring operatively engageable with said offset when projected into one of said openings of the lock.

3. In a car seal of the character described 35 comprising a lock having one end rigidly secured to one end of a pliable ribbon, the lock provided with an interior chamber

having an offset extending at right angles with the axis of the lock, an opening in the lock connecting with said chamber, 40 notches cut in the ribbon adjacent its free end, a spring supporting member having projections on one end engageable with said notches and a lip on the other end for rigidly securing one end of a spring, the free end of 45 the spring adapted to engage said offset when said free end of the ribbon is projected into said chamber a proper distance.

4. In a car seal of the character described, the combination with a flexible ribbon having one end permanently secured to one end of a lock, said lock having an interior chamber provided with an offset extending at a right angle with the longitudinal axis of the lock and an opening in its opposite end 55 intersecting with said chamber, of a pair of oppositely disposed notches cut in the ribbon adjacent its free end, a spring-supporting member having one end in engagement with said free end of the ribbon, lips on said 60 end of the spring-supporting member in engagement with said notches for rigidly securing the end to the ribbon, an upwardly struck lip on the free end of the spring-supporting member, and a locking-spring 65 having one end rigidly secured to said lip, the free end of said spring adapted to engage said offset when the free end of the ribbon is projected into said chamber a proper distance through the opening.

As evidence of the foregoing being my own, I have hereunto signed my name this 7th day of July, 1920.

FRANCIS M. VOLK.
